UNITED STATES PATENT OFFICE.

FRED ROTH, OF BROOKLYN, NEW YORK.

CIGARETTE-CASE.

1,320,926.

Specification of Letters Patent.

Patented Nov. 4, 1919.

Application filed April 10, 1919. Serial No. 289,011.

To all whom it may concern:

Be it known that I, FRED ROTH, a citizen of the United States, and a resident of the city of New York, borough of Brooklyn, county of Kings, State of New York, have invented certain new and useful Improvements in Cigarette-Cases, of which the following is a full, clear, and exact description.

My invention relates to a case for cigarettes, cigars, matches, etc., and more particularly to a two-part case designed and constructed to partly eject in sequence, one at a time, the cigarettes, cigars or matches, etc., therein contained by sliding one part 15 of the case over the other, which movement is effected by the thumb and index finger of one hand.

Although my case is, as above indicated, equally adaptable for carrying and dispensing cigarettes, cigars, matches and the like, I have chosen a cigarette case to illustrate 20 my invention.

Broadly stated, the present invention consists of a case composed of two parts, one 25 part the holder and the other the cover, in interlocked, sliding engagement, the holder being designed to carry cigarettes, cigars, matches, etc., and a spring, the latter serving to press the cigarettes, etc., gently against 30 one side of the holder, the end cigarette being held over a lug carried by the cover and aligned with an opening in the cover through which it is partly ejected by the relative sliding movement of the cover and holder.

I am aware that various cigarette cases 35 have been contrived which embody the broad general features of my case, as well as some of the details of construction thereof, but there are no cases of the type embraced with- 40 in the present invention which will operate satisfactorily with oval cigarettes, the form in which most of the so-called Egyptian and Turkish cigarettes are made.

The principal object of the present invention, therefore, is to provide a cigarette case 45 designed and constructed to automatically dispense cigarettes, etc., therein contained, one at a time in sequence, and which will function equally well with oval cigarettes as 50 with those round in cross section.

A further object of my invention is to provide a cigarette case of the class indicated especially suitable for cigarettes oval in cross section, and which will be simple and inexpensive to manufacture, efficient and reliable in operation and neat in appearance.

With the above and other objects in mind, reference is to be had to the accompanying drawings illustrating the preferred embodiment of my invention, in which similar reference characters refer to corresponding parts throughout, and in which,

Figure 1 is a side view of the case in perspective with a portion of the side wall of the holder broken away to expose the contents thereof, and the end leaf of the spring contained therein pressing against the row of cigarettes.

Fig. 2 is a plan view of the case in section taken along the line 2—2, Fig. 3, and looking 70 in the direction indicated by the arrow.

Fig. 3 is a cross section of the case taken along the line 3—3, Fig. 2, and looking in the direction indicated by the arrow.

Fig. 4 is a cross section of the case taken 75 along the line 4—4, Fig. 2, and looking in the direction indicated by the arrow.

Fig. 5 is an end view in perspective of the case.

The cigarette case is made up of two parts, 80 the holder A and the cover B. The holder A consists of a single sheet of metal stamped out to form an outer wall 6, with upturned edges forming end walls 7, 8 and 9 and flange 10, at right angles thereto, and an inner 85 short wall 28, parallel thereto, forming a pocket for the cigarettes. End wall 9 extends only part way the width of the case, leaving an opening or slot 11, and has near its inner edge a depression 12, for purposes 90 hereinafter explained. Walls 8 and 9, and flange 10 are depressed near their edges to form grooves 13, 14 and 15 respectively, extending the entire length of said walls and flange.

The cover B is likewise formed of a single sheet of metal stamped to form an outer wall 16 with three upturned edges constituting end walls 17, 18 and 19. Edge 20 of outer wall 16 is unflanged. Wall 18 is cut off a 100 short distance from wall 17 to provide a rectangular opening 26 through which the cigarettes are ejected. The end of wall 17 is turned in to form lug 27. The edges of each of end walls 17, 18 and 19 are bent over or 105 slightly flanged producing flanges 21, 22 and 23. Flanges 21, 22 and 23 fit respectively into grooves 14, 15 and 13 and lock the holder A and cover B together, at the same time permitting them to slide relative to each other. 110 The lug 27, fitting into the opening or slot 11, also serves to lock the holder A and cover B

together. When it is desired to fill the case with cigarettes, holder A and cover B are separated by sliding these parts relative to each other to the position indicated in Fig. 1, 5 and then forcing them out of engagement by pressing outwardly near the bottom of both the holder and the cover. Similarly when closing the case after filling, the lug 27 is first placed in slot 11, under the first cigarette 10 to be ejected, and the parts are then locked together by pressing inwardly on the outer sides of the holder and cover near the bottom.

Contained within the holder A is a leaf 15 spring 24, which I prefer to make of a single piece of spring brass. The spring is bent to form four leaves, the outer leaf 24^A bearing against one side of the case, and the leaf 24^B abutting against the row of cigarettes 25, 20 contained in the case. The free ends 24^c and 24^d respectively of the outer leaves 24^A and 24^B are bent outwardly, as are also the bent-over ends 24^e and 24^f. The purpose of the outward bend 24^e of leaf 24^B is to exert a 25 pressure near the bottom of the cigarette next to the spring, as the cigarette in alinement with the opening 26, and over lug 27, is forced up by said lug 27, as the holder A and cover B are separated longitudinally. 30 This pressure is followed by a pressure near the top of the cigarette next the spring exerted by bend 24^c, as the partly ejected cigarette is withdrawn by hand. The pressures exerted by the bends 24^e and 24^f on the cigarette 35 adjacent thereto are communicated of course to the entire row of cigarettes in the case, and the effect is to keep the row straight and the next cigarette to be ejected in position over the lug 27 and in register with 40 opening 26. The purpose of outward bends 24^d and 24^f of leaf 24^A is simply to add more spring to the leaf. I find in practice that where an ordinary flat leaf spring is used it is impossible to maintain the straight alinement of the cigarettes in the case, due to the 45 fact that the pressure of the spring upon the row of cigarettes is either near the bottom or near the top but only in one or the other place. Where a continued pressure is applied 50 near the bottom of the row, the cigarettes will be slanted crosswise of the case more and more as the cigarettes are withdrawn, until the cigarette next to be ejected is entirely out of line with the opening, when 55 the case can no longer be operated. Where a continued pressure is applied near the top of the row, the cigarettes will likewise be slanted crosswise of the case, which slant will increase as the cigarettes are withdrawn, 60 until the cigarette next to be ejected is out of line with and off the lug, and at an angle with the ejection opening, also resulting in the choking of the case.

By bending outwardly the leaf of my 65 spring adjacent to the row of cigarettes, as

described, its pressure is applied first near the bottom and then near the top of the row, thus always keeping the row straight. This is of the utmost importance where the cigarettes have an oval cross section, for if a row 70 of such cigarettes in the holder is permitted to slant, the shape of the cigarettes makes it impossible not only to eject them through the opening in the holder, but causes them to work up on one another in such manner as to 75 result in congestion, disturbed alinement and blocking.

The manner of using the case and the operation of its parts have, in the main, already 80 been indicated throughout the foregoing description. Summarizing, the holder A and cover B of the case are first forced out of engagement after being brought to the relative position indicated in Fig. 1. Cigarettes 85 are filled into the holder A, the spring 24 meanwhile being held in compression against the end wall thereof opposite that adjacent to the opening 26. When the cigarettes are properly alined, the spring is released 90 against them, and holder A and cover B are locked together, the lug 27 being first placed in slot 11 under the end of the first cigarette to be ejected. The cigarettes are dispensed one at a time by grasping the case with the thumb and index finger of one hand and 95 sliding the holder B and cover A longitudinally of each other to the limit of motion. This operation causes the lug 27 to force the first cigarette partly out of the holder. The two parts of the case are now brought back 100 to the normally closed position, when the end of the first cigarette will protrude from the case, from which it may then be withdrawn by hand. As the first cigarette is withdrawn, the spring 24 forces the next cigarette 105 over lug 27 and in alinement with opening 26. The operation is then repeated. The depression 12 in wall 9 is to prevent the tearing of the cigarette wrapper by the end of wall 9, as the cigarettes are extracted from 110 the case.

Having thus described my invention, I claim as new and desire to protect by Letters Patent,

1. The combination of a case for cigarettes 115 and the like, of the class described, comprising a holder and cover in interlocked sliding engagement and a lug for ejecting singly and in sequence the contents thereof through openings in register in said holder and said cover, of an instrumentality for exerting a pressure first, upon the lower end of the row of cigarettes and the like, contained in the holder as one of the same is partly ejected, followed by a pressure upon the upper end of said row as the said cigarette or the like is withdrawn from the case by hand, said instrumentality comprising a four leaf spring, 120 the ends of the outer leaves of which are bent outwardly. 125

2. A cigarette case, comprising a holder and a cover, flanges on three of the upturned edges or walls of said cover, complementary grooves in the struck up edges of said holder, 5 said flanges fitting into said grooves to hold the parts of the case in interlocked, sliding engagement; a rectangular opening in said cover and in said holder in register therewith; a lug in line with said openings, and 10 an instrumentality for exerting a pressure first upon the lower end of the row of cigarettes contained in the holder as one of the same is partly ejected, followed by a pressure upon the upper end of said row as the said cigarette is withdrawn from the case by 15 hand, said instrumentality comprising a one-piece, four leaf spring the ends of the outer leaves of which are bent outwardly.

FRED. ROTH.
